[57] **CLAIM**

The ornamental design for attachment device for attaching a self-steering system to the transom of a sailboat, as shown and described.

DESCRIPTION

FIG. 1 is a left, front perspective view of an attachment device for attaching a self-steering system to the transom of a sailboat showing my new design, the four bolts which attach the attachment device to the transom are shown in dotted lines for illustrative purposes only;

FIG. 2 is a left side elevational view thereof;

FIG. 3 is a rear elevational view thereof;

FIG. 4 is a front elevational view thereof;

FIG. 5 is a top plan view thereof; and,

FIG. 6 is a bottom plan view thereof.

The right side of the attachment device (not shown) is symmetrical with the left side view of FIG. 2.
